CALCULATING MACHINE

Robert L. Muller, Detroit, Mich., assignor to Burroughs Adding Machine Company, Detroit, Mich., a corporation of Michigan

Application January 30, 1933, Serial No. 654,190

22 Claims. (Cl. 235—60)

This invention relates to a calculating machine. It is particularly concerned with the operation and control of a consecutive numbering mechanism.

5 The general object of the invention is to provide an improved construction and control for the consecutive numbering mechanism of a calculating machine.

10 A more particular object is to provide an improved carriage control for a consecutive numbering mechanism.

15 Another object is to provide improved control of the printing and the advancing of a consecutive numbering mechanism so that a consecutive number may be printed a given number of times and so that the consecutive numbering mechanism can be advanced at desired times.

20 Another object is to provide improved control of a consecutive numbering mechanism by the total taking means of a calculating machine.

25 Other and more particular objects will appear from the following specification and drawings:

An embodiment of the invention is shown in the accompanying drawings in which:

25 Figure 1 is a right side elevation of a calculating machine with the invention incorporated therein, the parts being in normal position.

30 Fig. 2 is a perspective view showing the invention and the portion of the calculating machine more particularly associated with it, the view being taken looking at the machine from the rear.

35 Fig. 3 is a partial perspective of the consecutive numbering mechanism and some of the controls therefor, the view being taken from the rear.

Fig. 4 is a partial right side elevation and section with the parts in the position they occupy when the consecutive numbering mechanism is ready for printing.

40 Fig. 5 is a partial right side elevation and section showing the controls in the position they occupy during the forward machine stroke but before the printing hammers have been released, one of the latching devices hereinafter described being omitted.

45 Fig. 6 is a view similar to Fig. 5 after the printing hammers have fired at the end of the forward machine stroke.

Fig. 7 shows a journal form comprising one part of a set of forms that may be used with the invention.

50 Figs. 8 and 9, respectively, show the checks and check stubs that may be used with the journal shown in Fig. 7 to make up a set of forms illustrative of one kind of work that may be done on the machine.

Fig. 10 shows another set of forms that may be used.

Fig. 11 shows the carriage tappets employed with the set of forms shown in Fig. 10.

5 The invention is shown applied to a Burroughs calculating machine the construction of which is well known so that only a brief description of it will be given here.

The machine includes a plurality of amount keys 1 controlling the differential movements 10 of actuator racks 2. Cooperating with these actuator racks is an addition-subtraction registering mechanism comprising two sets of pinions 3 and 4. The actuator racks 2 are carried by arms 5 pivoted at 6 and the rear ends of these 15 arms carry digit types 7 which are differentially positioned at the same time that the actuator racks are positioned. Suitable printing mechanism is provided including printing hammers 8 (Fig. 4) which are fired at the proper time to 20 drive the digit types into engagement with a ribbon 9 positioned along the printing line of a platen 10 carried by a traveling paper carriage 11.

The machine is given a forward and return stroke of operation, the forward stroke being by 25 hand or by a motor and the return stroke being under the influence of springs. During the forward stroke, a shaft 12 (Fig. 1) is rocked clockwise against the tension of spring 13. During the return stroke the shaft is returned counter-clockwise by the spring 13 to normal position. Fixed to the shaft 12 is a crank arm 14 which is yieldingly connected by springs 15 to a secondary member 16 pivoted on a shaft 17. This 30 secondary member rocks clockwise during a forward stroke and counterclockwise during the return stroke of the machine.

A toggle mechanism is provided including the parts 18 and 19 (Fig. 4) which serve to hold the parts in position at the end of the forward stroke 40 until after the necessary machine operations have taken place, after which the toggle is broken and the return stroke of operation of the machine is performed.

Consecutive numbering counter

45

The consecutive numbering counter is best shown in Fig. 3. It includes a plurality of pinions or wheels 20 rotatably mounted on a shaft 21 carried by a lever or member 22 pivoted on a 50 stud shaft 23 supported by a stationary frame or bracket member 24. The wheels carry suitable digits on their periphery for printing ten consecutive numbers as will be later described.

The details of the wheels form no part of the 51

present invention and their construction may be varied to suit the requirements.

Means for causing consecutive numbering mechanism to print a consecutive number

A printing operation of the consecutive numbering mechanism involves moving the consecutive numbering counter into engagement with the platen on the paper carriage, it being understood, of course, that the ink ribbon 9 intervenes so as to make an impression on the paper. This movement of the counter is obtained by rocking the lever 22 on its pivot 23 to move the counter wheels into and out of engagement with the platen. For the purpose of rocking the lever 22, a bell crank lever comprising the arms 25 and 26 is pivoted on a stud 27 in the stationary bracket 28 of the machine. The arm 25 of this bell crank lever carries a stud 29 operating in the slot 30 in the lower end of the arm 22. Pivoted on the stud 27 is an arm 31 urged counterclockwise as viewed in Fig. 3 by a spring 32 against a stud 33 on the bell crank lever arm 26. The lower end of the arm 31 is positioned in the path of a shaft 34 (Fig. 2) carried by the crank arm 16 fixed to the shaft 12. During each operation of the machine the shaft 34 is moved rearwardly, or clockwise as viewed in Fig. 2, into engagement with the lower end of the arm 31. This moves the arm 31 counterclockwise as viewed in Fig. 2, or clockwise as viewed in Fig. 3. This movement of arm 31 tensions a spring 35 connected between the arm 31 and a stud on the bell crank arm 26. If the bell crank 25-26 is held against movement, as will be hereinafter explained, it follows that, during each operation of the machine, the spring 35 will be tensioned and it will exert a force on the bell crank 25-26 tending to rock it clockwise as viewed in Fig. 3. The bell crank, in turn, tends to rock the lever 22 counterclockwise. In other words, during each operation of the machine the consecutive numbering mechanism is urged toward printing position by a means that is tensioned during each operation of the machine.

Automatic advancing means

It is necessary to advance the consecutive numbering wheels unit by unit and provision is made for doing this as an incident to the printing operation of the consecutive numbering mechanism.

Referring to Fig. 3, it will be observed that a yoke 40 is pivoted on the shaft 21 on which the consecutive numbering wheels 20 are journaled. This yoke 40 has an upwardly extending arm 41 carrying a stud 42 operating in a slot 43 in the stationary support 24, the slot 43 being eccentric to the axis of the pivot 23 of the lever 22. When the lever 22 is rocked counterclockwise as viewed in Fig. 3, stud 42 operating in the slot 43 causes the yoke 40 to be rocked clockwise a predetermined distance.

Pivoted on the yoke 40 is a second yoke 44 having a series of pawl fingers 45 (Fig. 4) adapted to engage ratchet teeth 46 on their respective counter pinions 20 (Figs. 1 and 4). This second yoke 44 is urged clockwise as viewed in Fig. 4 by a spring 47.

The yoke 44 carrying the pawl fingers 45 carries a pawl finger for each pinion. The arrangement is such that the pawls for the tens, hundreds and higher order pinions are active only when the pinion of next lower order has moved from its "9" directly to or through its "0" position.

In other words, the pawls in orders higher than the units order act only to effect a tens transfer. Details of construction of this mechanism do not form a part of the present invention and since they are well known they have not been illustrated or described in detail. In referring to the pawl fingers 45 in the following description reference will be made to the units order only.

When the yoke 40 is rocked counterclockwise as viewed in Fig. 4, the pawl 45 for the units order moves over the teeth of its ratchet 46 slightly more than one tooth distance so that the pawl engages the next succeeding tooth of the ratchet when its direction is reversed. As the consecutive numbering mechanism returns to normal, the yoke 44 is rocked clockwise as viewed in Fig. 4 and the pawl finger 45 engages the next ratchet tooth and moves the "units" pinion one step forward, i. e., it advances the consecutive numbering mechanism a unit.

It is to be observed that, during each printing operation of the consecutive numbering mechanism, the advancing means tends to automatically advance the consecutive numbering mechanism a predetermined amount. Means has been provided for disabling this automatic advancing means under predetermined conditions but this will be later described.

Restraining means for insuring that consecutive numbering mechanism will print only during the proper time in the cycle of operation of the machine

It is desirable that the consecutive numbering mechanism operate at the proper time in the cycle of operation of the machine and, to insure this, means is provided for controlling the printing operation of the consecutive numbering mechanism.

Referring to Fig. 2, it will be observed that the arm 22 carrying the consecutive numbering counter has a lateral lug 50. A number of latches cooperate with this lug to restrain movement of the arm 22 and we will first describe the restraining means which controls the time during the cycle of machine operation that the consecutive numbering mechanism will print.

This restraining means comprises a latch 51 pivoted at 52 and urged clockwise as viewed in Fig. 2 by a spring 53. The latch is thus normally held in position to obstruct clockwise movement of lug 50 (Fig. 2) on the arm 22. But, at a certain time during the operation of the machine, the latch is released.

Referring to Fig. 4, a link 54 is pivoted to the member 120 fixed to shaft 17 which shaft, it will be recalled, is first rocked clockwise and then returned counterclockwise during each operation of the machine. The link 54 is connected at its upper end to a yoke member 55 pivoted at 56. Yoke member 55 has an arm carrying a stud 55a operating in slot 57 in a pivoted latch releasing hammer 58 pivoted at 56 and urged clockwise by a spring 59. The releasing hammer 58 is normally restrained against movement by a latch 60 having a hooked end adapted to engage a shoulder 61 on the hammer 58, the latch being urged clockwise (Fig. 4) by a spring 62. The printing mechanism includes arms 63 of which one is shown carrying a bail 64 which supports a plurality of latches 65 that operate the printing mechanism in a manner well understood in Burroughs machines. The latch 60 is provided with a tail 66 positioned in the path of the end portion of

bail 64 so that, at a certain time in the counter-clockwise movement of the bail (Fig. 4), which is shortly after the printing hammers 8 have been fired, the latch 60 is rocked counterclockwise by 5 bail 64 to release the hammer 58. This permits the hammer 58 to move under the urge of its spring 59, the stud 55^a having moved in the slot 57 so as to permit such movement. The hammer 58 has an abutment face or end 67 (Fig. 5) 10 and, positioned in the path of this abutment, is a stud 68 carried by the latch 51. Accordingly, when the hammer 58 is fired the latch 51 is released.

To summarize, these parts operate as follows: 15 As the machine is operated during a forward stroke, the bail 64 is rocked counterclockwise (Fig. 4) to cock the hammers 8 of the printing mechanism. These hammers are released near the end of the forward stroke of the machine 20 in a well-known manner. Also, near the end of the forward stroke and slightly after the hammers have been released, the bail 64 engages the tail of the latch 60 and rocks it counterclockwise. This releases the hammer 58 which is 25 thereupon moved clockwise by its spring 59. The clockwise movement of the hammer 58 causes the abutment face 67 to engage the stud 68 and release the latch 51 so as to free the consecutive 30 numbering mechanism for a printing operation slightly after the regular printing mechanism is operated and at the end of the forward stroke of the machine.

The parts are restored during the return stroke 35 of the machine at which time the stud 55^a engages the end of the slot 57 and returns the hammer 58 counterclockwise as viewed in Fig. 4. This releases the latch 51 for return to normal under the urge of its spring 53. The latch 51 does not, of course, return to latching position 40 until the arm 22 has returned to normal and the arm 22 does not return to normal until the shaft 34 (Fig. 2) has returned and released the member 31. This enables spring 32 to return the bell crank 25—26 to normal and moves the consecutive 45 numbering mechanism out of printing position. As the lever 22 moves back to normal its lug 50 passes over the shoulder of the latch 51 and allows the latter to return to normal position under the influence of its spring 53.

50 From the above it will be clear that a restraining means has been provided for the consecutive numbering mechanism which controls the latter so that it will print only at the desired time during a cycle of machine operation, which time is 55 slightly after the operation of the regular printing mechanism and near the end of the forward stroke of the machine.

Carriage control of consecutive numbering printing

60 Provision has been made for controlling the consecutive numbering mechanism automatically so that consecutive numbers can be printed in any predetermined columnar position of the carriage. 65

Referring to Fig. 2, the paper carriage is provided with one or more cam plates or tappets 70 adapted to engage, in predetermined columnar positions of the carriage, a roller 71 carried by 70 one arm 72 of a yoke 13 pivoted on the back panel of the machine. The other arm 14 of this yoke is connected by a link 75 to an arm 76 fixed on a rock shaft 77. The rock shaft 77 has a latch 78 fixed to it and this latch cooperates with 75 the lateral lug 58 on the arm 22 carrying the

consecutive numbering wheels 20. This latch restrains the consecutive numbering mechanism against printing and must be released in order that a printing operation may take place. Such release is effected by the engagement of the cam plate 70 with the roller 71 which rocks the shaft 77 so as to move the latch 78 counterclockwise. For convenience in description, the restraining means including the latch 78 will be referred to as the second restraining means.

10 Provision is made for automatically disabling the advancing means for the consecutive numbering mechanism when the carriage releases the consecutive numbering mechanism for printing. Referring again to Fig. 2, it will be observed that 15 the latch 78 has an upwardly extending arm 80 positioned over a stud 81 carried by a slide plate 82 urged upwardly by a spring 83. This slide plate carries a stud 84 on its upper end which is positioned over a tail 85 (Fig. 4) on the pawl 20 finger 45. When the slide 82 is in its upper position, shown in Fig. 1, the pawl finger 45 is free to engage its ratchet 46 and the automatic advancing means is in operative or enabled condition. But, when the slide 82 is moved downwardly to 25 the position of Fig. 4, the stud 84 engages the tail 85 and holds the pawl finger 45 out of the path of its ratchet wheel so that, even though the yokes 40 and 44 are rocked, the wheels 20 will 30 not be advanced.

From this it will be seen that, when the shaft 77 is rocked by carriage tappet 70 to release the latch 78, the tail 80 will engage the stud 81 and move the slide 82 downwardly so as to automatically disable the advancing means for the 35 consecutive numbering mechanism.

The consecutive numbering mechanism is controlled by a third latching or restraining device which includes a latch 90 adapted to engage the lug 50 of the arm 22. This latch is a part of an 40 irregular shaped member 91 pivoted at 92 and urged counterclockwise as viewed in Fig. 2 by a spring 93. This irregular shaped member has an upwardly extending cam arm 94 positioned in the path of the stud 81, the parts being proportioned 45 so that when the stud 81 is moved downwardly as heretofore explained, it will engage the cam edge of the arm 94 and rock the latch 90 out of the path of the lug 50.

From the description thus far given, it will be 50 clear that, in a predetermined columnar position of the carriage, both of the latches 78 and 90 will be released and the automatic advancing means will be automatically disabled. When the latches 78 and 90 are released, the lug 50 can 55 move a slight distance so as to move over these latches to prevent them from returning but it cannot immediately move far enough to allow the consecutive numbering mechanism to move to printing position because of the latch 51. 60 But, during the operation of the machine, the latch 51 is released at the proper time, as heretofore explained, and thereupon the consecutive numbering mechanism operates to print a consecutive number.

When the paper carriage moves away from the column in which the cam plate 70 engages the roller 71, the parts return to normal under the influence of their various springs.

It is to be understood that the carriage can 70 be provided with as many of the cam plates 70 as is desired and that, when so provided, the consecutive numbering mechanism will repeat print a consecutive number in any desired number of columnar positions of the carriage and this con- 75

secutive number will be the same number because the advancing means is disabled during each of these printing operations.

5 Total key control of consecutive numbering mechanism

Generally speaking, after a total has been taken, it is desirable to advance the consecutive numbering mechanism a predetermined amount and, in order that this may occur, a control has been provided which will now be described.

10 The carriage is provided with one or more cam plates 100 similar to the cam plates 70 but not quite as large so that when they engage the roller 71, the yoke 73 will not be rocked as far as when the roller is engaged by a cam plate 70. This movement is far enough to release the latch 78 but the arm 89 that engages the stud 81 does not move the slide 82 down far enough to disable the 15 automatic advancing means. Accordingly, while the latch 78 will be released, the automatic advancing means will not be disabled in the columnar position where one of the cam plates 100 is operative.

20 25 In total taking operations, a blank stroke of operation of the machine is usually necessary before the total is taken. This blank stroke occurs before the total key is depressed. In fact, the total key is sometimes locked against depression until the spacing stroke has been given. Inasmuch as the cam 100 conditions the parts so that the advancing means remains operative, it follows that, if the consecutive numbering mechanism were allowed to print during the spacing 30 stroke, an impression would occur after which the consecutive numbering mechanism would be advanced a unit. Then, during the actual totaling operation, the carriage remaining in its same position, the consecutive numbering mechanism would print a second time but would print a different number. This is undesirable.

35 40 But such operation is prevented by the restraining means including the latch 90. The rocking of the shaft 77 by the cam plate 100 is not sufficient to move arm 80 and stud 81 down far enough to release the latch 90. Accordingly, during the spacing stroke the consecutive numbering mechanism does not print and it is not advanced. Provision is then made for releasing the consecutive 45 50 numbering mechanism under the control of the total key.

55 Referring to Fig. 1, it will be observed that the total key T is connected to a bell crank lever 101 which, when the total key is depressed, is rocked counter-clockwise. This bell crank lever is connected by a link 102 to a crank arm 103 fixed to a shaft 104. The shaft 104 has a second crank arm 105 fixed to it. Connected to crank arm 105 is a link 106 provided with an abutment face 107 positioned in front of a bell crank latch 108 urged counterclockwise as viewed in Fig. 1 by a spring 109. This latch has a lug 110 which normally restrains a pivoted arm 111 against movement by a spring 112. The lower end of the member 111 carries a stud 113 engaging in a slot in a releasing latch 114 pivoted at 115. The irregular shaped member 91, of which the latch 90 is a part, has a lateral lug 116 in the path of the member 114.

60 65 70 When the total key is depressed, the bell crank latch 108 is rocked clockwise and the member 111 is released, whereupon it is moved counterclockwise by its spring 112. When the member 111 moves counterclockwise, the member 114 is moved 75 clockwise and the latter engages the lateral lug

116 and moves latch 90 clockwise to release the consecutive numbering mechanism.

75 While the release has been shown as under the control of the total key, it is to be understood that it can be placed under the control of other control keys or manipulative members on the machine.

80 When a sub-totaling operation takes place, as in column C, Figs. 8 and 9, depression of the total key causes the member 114 to engage the lug 116 and move the restraining latch 90 clockwise downwardly out of the path of the lug 50. Pivoted to the restraining latch 90 at 117 is an abutment 118 which moves downwardly with the restraining latch 90 and is rocked counterclockwise to a position beneath the lug 50 by its spring 119. When the member 114 is restored counter-clockwise on the forward stroke of the machine following depression of the total key, the upper end of the abutment 118 engages the 10 15 20 underside of the lug 50 and prevents the restraining latch 90 from restoring to its Fig. 2 position behind the lug 50 until the lug 50 has been released by the restraining latch 51 and has moved clockwise with the arm 22 to fire the consecutive numbering wheels. If the lug 118 were not provided, the restraining latch 90 would tend to return to its Fig. 2 position and prevent clockwise movement of the firing arm 22.

25 30 35 40 45 From the above it will be clear that, in a second predetermined columnar position of the carriage, the consecutive numbering mechanism can be released for a printing operation without disabling the automatic advancing means. In this second predetermined columnar position, the printing operation of the consecutive numbering mechanism is under the joint control of the carriage and the total key. The consecutive numbering mechanism is not advanced because the release of the latch 90 by the total key does not move the slide 82 downwardly nor does the small tappet 100 move it down sufficiently to disable the advancing means.

50 55 60 65 70 To put it another way, and taking into consideration the control by the carriage tappet 70 as well as tappet 100, in one predetermined columnar position both the second and third restraining devices are released and the advancing means is disabled. In a second predetermined columnar position the second restraining means is released without releasing the third and without disabling the advancing means. In this second predetermined columnar position the third restraining means can be released by a manually manipulatable member which, in this instance, 75 is the total key.

75 80 85 90 95 Since any suitable number of cam plates 100 can be provided, and since the total key can be operated in desired columnar positions of the carriage, it follows that the consecutive numbering mechanism may be advanced in as many columnar positions as is desired.

Example of work

The example of work illustrated in Figs. 7, 8 and 9 consists in making certain entries on a check stub, which are duplicated on a journal sheet, and in then writing a check. The various working positions of the paper carriage are represented as A, B, C, D, E and F.

90 95 A journal sheet marked "Journal" remains around the platen during the writing of various checks and the entries on it are simply duplicates of the entries on the check stubs, suitable carbon paper being interposed for this purpose.

With the paper carriage in the position "A", the gross amount earned by an employee is entered on the amount keys and the machine operated. In this instance, the gross amount is 5 "50.00" and the number of the check to be written is "4986". In this position of the carriage one of the larger tappets 70 is operative so that the consecutive numbering mechanism is conditioned for printing and the advancing means for 10 said mechanism is disabled. This means that, when the machine is operated, the number of the check "4986" will be printed, but the consecutive numbering mechanism will not be advanced.

The paper carriage then moves to the next position "B" where no carriage tappets such as 15 70 or 100 are employed and the consecutive numbering mechanism is latched against printing. In this column the deductions from the pay of the employee are entered and printed, these being, in the example, "\$2.25".

The carriage next moves to position "C" where the net pay due the employee is calculated by taking a sub-total from the machine. In this 20 position, the carriage is provided with one of the smaller tappets 100 which partially releases the consecutive numbering mechanism as heretofore described, but does not disable the automatic advancing means for the consecutive numbering mechanism. During the spacing stroke the consecutive numbering mechanism will not be operated, but, during the actual subtotaling operation, the consecutive numbering mechanism will first print the previous consecutive number, that is, "4986" on the forward stroke of the machine, 25 after which the consecutive numbering mechanism will be advanced a unit, that is, to 4987 during the return stroke of the machine. In the description of the invention heretofore given the control of the printing operation of the consecutive numbering mechanism has been described with particular reference to a total key as distinguished from a sub-total key, whereas, in the work above mentioned, a sub-total has been mentioned for column "C" of the carriage. 30 The control of the consecutive numbering mechanism is the same no matter whether a total or a sub-total is taken, because, in the machine with which the invention has been illustrated, the bell crank lever 101 (Fig. 1) is rocked no matter 35 whether a total or sub-total is taken. In fact, in the particular machine illustrated, the carriage controls the machine so that a sub-total can be taken by depressing the total key T.

After operations have been completed in column "C" the paper carriage moves successively to columns D, E and F, to write the check. No carriage tappets 70 or 100 are present in columns D, E and F, and hence the consecutive numbering mechanism does not operate in these columns.

When the carriage returns to column A, the machine is ready for the entry of the gross pay of the next employee which, in this instance, is 45 "\$40.00". It will be recalled that, in column A, a carriage tappet 70 is provided which enables the consecutive numbering mechanism to print, but disables the advancing means. It will also be recalled that the consecutive numbering 50 mechanism was automatically advanced to "4987" when the machine operated to print a sub-total in column C. Accordingly, when the machine is operated in column A, the gross amount earned, namely, "\$40.00" will be printed 55 and the number of the check "4987" will be en-

tered in the check column. Operations are then continued as heretofore explained.

Second example of work

Another form of work is shown in Fig. 10 in 5 which two sets of carriage tappets are employed and in which the third restraining latch 90 and control by the total key are omitted.

When the latch 90 and the total key control 10 are omitted, the consecutive numbering mechanism is released for printing in each of the columns in which carriage tappets are provided because, it will be recalled, both the large tappets 70 and the small tappets 100 release the latch 78. The difference between the use of a large tappet 70 15 and a small tappet 100 under these conditions is that in one case, namely, with the large tappet 70, the means for advancing the consecutive numbering mechanism is disabled whereas, when the smaller tappet 100 is used, said advancing means 20 is not disabled.

Referring to Fig. 10, the work consists in making entries on stubs of checks and in writing the checks but no calculations are performed with respect to the amount due the receiver of the 25 check.

In column A, one of the large tappets 70 is in position. The salary due the employee, "\$51.60", is set up on the keyboard and the machine is operated. During the operation \$51.60 will be 30 printed as will also the consecutive number "1234". Since the large tappet 70 is in position, the consecutive numbering mechanism will not be advanced but will remain in condition to print 35 1234 a second time.

When the carriage is moved to column B, a small tappet 100 comes into play and a hammer blocking mechanism of the usual Burroughs type (not shown) blocks the printing of the amount \$51.60. The result is that, when the machine is 40 operated, the consecutive number, "1234", will be printed at the end of the forward stroke of the machine in column B. On the return stroke of the machine in this column, the consecutive numbering mechanism will be advanced one unit, that is, to "1235", because the small tappet 100 did not move the slide 82 down sufficiently to disable the pawl fingers 45.

When the carriage moves to column C, no tappets are active to control the consecutive numbering mechanisms. The amount \$51.60 will be 50 repeat printed but the consecutive numbering mechanism will not be operated to print a consecutive number. It remains at "1235".

When the carriage moves to column D, a second 55 large tappet 70 becomes operative. In this column a new salary amount, namely \$40.10 is entered on the keyboard and the machine operated. The result is that \$40.10 is printed and the consecutive number "1235" is also printed. But the consecutive numbering mechanism will not be advanced a unit in this column because the large tappet 70 has moved slide 82 down sufficiently 60 to disable pawl fingers 45.

When the carriage moves to column E, one of the small tappets 100 becomes active and the hammer blocking mechanism acts to prevent printing the amount \$40.10. During the forward stroke of operation the consecutive number "1235" is printed and, then, during the return stroke, the consecutive numbering mechanism is advanced a unit to "1236".

When the carriage moves to column F there is no tappet that is active and, in this column, the amount \$40.10 is repeat printed without a print- 75

ing operation on the part of the consecutive numbering mechanism.

The carriage then returns across the machine to start in column A again where operations are repeated as above described for the second set of checks illustrated in Fig. 10.

From this it is to be observed that any desired number of tappets 70 or 100 can be employed and the same consecutive number can be repeated a number of times or the consecutive numbering mechanism can be automatically advanced when required.

It is to be understood that this sample of work is only one of the many that may be performed and it is likewise to be understood that variations may be made in the structure illustrated without departing from the spirit and scope of the invention as defined by the appended claims.

I claim:

1. A machine of the class described having a traveling paper carriage, a consecutive numbering mechanism, means operable during each operation of the machine to cause a printing operation of said consecutive numbering mechanism, a restraining means normally holding said consecutive numbering mechanism against movement to printing position but released at a predetermined time during each operation of the machine, additional restraining means for said consecutive numbering mechanism, and means controlled by said paper carriage for releasing said additional restraining means in predetermined columnar positions of said carriage.

2. A machine of the class described having a traveling paper carriage, a consecutive numbering mechanism, means operable during each operation of the machine to cause a printing operation of said consecutive numbering mechanism, a latch restraining said consecutive numbering mechanism against movement to printing position, means operating automatically during each operation of the machine to release said latch at a predetermined time during said machine operation, additional latching means restraining said consecutive numbering mechanism, and means actuated by said paper carriage for releasing said additional latching means in predetermined columnar positions of said carriage.

3. A machine of the class described having a traveling paper carriage, manually controlled means for conditioning the machine to perform a predetermined function, a consecutive numbering mechanism, means operable during each machine operation to cause a printing operation of said consecutive numbering mechanism, and restraining means under the joint control of said paper carriage and said manually controlled means operable to release said consecutive numbering mechanism in predetermined columnar positions of said carriage.

4. A machine of the class described having a traveling paper carriage, manually controlled means for conditioning the machine to perform a predetermined function, a consecutive numbering mechanism, means operable during each machine operation to cause a printing operation of said consecutive numbering mechanism, restraining said consecutive numbering mechanism against printing but released at a predetermined time during each machine operation, and additional restraining means under the joint control of said paper carriage and said manually controlled means operable to release said consecutive numbering mechanism in predetermined columnar positions of said carriage.

5. A machine of the class described having a traveling paper carriage, total-taking means, a consecutive numbering mechanism, means operable during each operation of the machine to cause a printing operation of said consecutive numbering mechanism, and restraining means under the joint control of said paper carriage and said total-taking means for releasing said consecutive numbering mechanism in predetermined columnar positions of said carriage. 5

6. A machine of the class described having a traveling paper carriage, a consecutive numbering mechanism, means operable during each operation of the machine to cause a printing operation of said consecutive numbering mechanism, two restraining devices for restraining said consecutive numbering mechanism against printing, means controlled by said paper carriage for releasing both of said restraining devices in a predetermined columnar position of the carriage, said carriage controlled means operating in a second predetermined columnar position to release one of said restraining devices without releasing the other, and manually controlled means for releasing said second restraining device in said second predetermined columnar position of the carriage. 10

7. A machine of the class described having a traveling paper carriage, a consecutive numbering mechanism, means for urging said consecutive numbering mechanism to print a consecutive number, two restraining devices for restraining said consecutive numbering mechanism against printing, means controlled by the paper carriage in a predetermined columnar position thereof for releasing both of said restraining devices, said carriage controlled means operating to release one of said restraining devices without releasing the other in a second predetermined columnar position of said carriage, and key controlled means for releasing said second restraining device in said second predetermined columnar position of the carriage. 35

8. A machine of the class described having a traveling paper carriage, total-taking means, a consecutive numbering mechanism, means urging said consecutive numbering mechanism to print a consecutive number, two restraining devices for restraining said consecutive numbering mechanism against printing, means controlled by said paper carriage for releasing both of said restraining devices in a predetermined columnar position of said carriage, said carriage controlled means operating to release one of said restraining devices without releasing the other in a second predetermined columnar position of said carriage, 40 and means controlled by said total-taking means for causing said second restraining device to be released in said second predetermined columnar position. 50

9. A machine of the class described having a traveling paper carriage, a total-taking means, a consecutive numbering mechanism mounted to move to and from printing position, means urging said consecutive numbering mechanism toward printing position, a restraining device released 65 automatically during each machine operation but operable to restrain said consecutive numbering mechanism against movement to printing position except at the proper time during the cycle of operation of said machine, two additional restraining devices comprising a second and a third restraining device for restraining said consecutive numbering mechanism against movement to printing position, means controlled by said paper carriage for releasing both said second and third 70 75

- restraining devices in a predetermined columnar position of the carriage, said carriage controlled means being operable in a second predetermined columnar position of said carriage to release said 5 second restraining device without releasing said third device, and means controlled by said total-taking means for releasing said third restraining device in said second predetermined columnar position of said carriage.
10. A machine of the class described having a traveling paper carriage, manually controlled means for conditioning the machine to perform a certain function, a consecutive numbering mechanism, an advancing means for said consecutive numbering mechanism, means controlled by said paper carriage for causing said consecutive numbering mechanism to print the same consecutive number in predetermined columnar positions of the carriage, and means under the 15 joint control of said paper carriage and said manually controlled means in predetermined columnar positions of said carriage for causing said consecutive numbering mechanism to print said same consecutive number and to thereafter automatically advance a predetermined amount.
11. A machine of the class described having a traveling paper carriage, total-taking means, a consecutive numbering mechanism, an advancing means for said mechanism, means under the 20 joint control of said total-taking means and said paper carriage in predetermined columnar positions of said carriage for causing said consecutive numbering mechanism to print a consecutive number and be advanced a predetermined amount, and means controlled by said paper carriage for causing said consecutive numbering mechanism to print the same consecutive number in predetermined columnar positions of the carriage between the columnar positions in which 25 said consecutive numbering mechanism is advanced.
12. In a machine of the class described, a stationary support, a member pivoted to rock on said support, a shaft carried by said member, a plurality of consecutive numbering pinions rotatably mounted on said shaft, means for rocking said member to move said pinions to and from printing position, a yoke rockably mounted on said shaft and provided with a cam stud operating in a slot in said stationary support which slot is eccentric to the pivot of said member whereby, each time said member is rocked to move said pinions to and from said printing position, said yoke is rocked about said shaft for the purpose 30 of advancing said pinions.
13. A machine of the class described having a traveling paper carriage, a consecutive numbering mechanism, means operable to cause a printing of the number in said consecutive numbering mechanism, two devices normally preventing the printing of said consecutive number but being adapted to be conditioned to enable said consecutive number to be printed, means controlled by said paper carriage for conditioning both of 35 said devices in a predetermined columnar position of the carriage to cause the printing of said consecutive number, said carriage controlled means operating in another or second predetermined carriage position to condition one of said devices without conditioning the other, and manually controlled means operable in said second carriage position to condition said unconditioned device to cause the consecutive number to be printed.
- 75 14. A machine of the class described having a traveling paper carriage, a consecutive numbering mechanism, printing means operable to cause the consecutive number in said consecutive numbering mechanism to be printed, advancing means normally operated by said printing means as an incident to a printing operation, and means controlled by said paper carriage for conditioning said advancing means in a predetermined columnar position of said carriage to enable said printing means to repeat the printing of a consecutive number without advancing said consecutive numbering mechanism.
15. A machine of the class described having a traveling paper carriage, a consecutive numbering mechanism, printing means adapted to be 40 conditioned to cause the consecutive number in said mechanism to be printed, an advancing means for said consecutive numbering mechanism normally operating to advance said mechanism as an incident to the printing of a consecutive number, and means controlled by said paper carriage for disabling said advancing means and simultaneously conditioning said printing means for a printing operation.
16. A machine of the class described having a traveling paper carriage, a consecutive numbering mechanism, means conditioned by a cycle of operation of said machine to urge said consecutive numbering mechanism in a direction to print the consecutive number in it, restraining 45 means preventing said consecutive numbering mechanism from printing, an advancing means for said consecutive numbering mechanism normally operable to advance said mechanism after a consecutive number has been printed, and means controlled by said paper carriage for releasing said restraining means and disabling said advancing means.
17. A machine of the class described having a traveling paper carriage, a consecutive numbering mechanism, printing means for causing the consecutive number in said mechanism to be printed, an advancing means normally operable to advance said consecutive numbering mechanism as an incident to the printing of a consecutive number, means controlled by said paper carriage for causing the consecutive number in said numbering mechanism to be printed in a predetermined columnar position of the carriage and for automatically disabling said advancing 50 means for said printing operation, and means under the joint control of said paper carriage and a manipulative member for causing a consecutive number to be printed in another carriage position with said advancing means in operative condition.
18. A machine of the class described having a traveling paper carriage, total taking means, a consecutive numbering mechanism provided with means for enabling consecutive numbers to be printed, advancing means normally advancing said consecutive numbering mechanism after a number has been printed, means under the control of said paper carriage causing a consecutive number to be printed and disabling said advancing means, and means under the joint control of said paper carriage and said total taking means for causing a printing of a consecutive number while said advancing means remains in operative condition.
- 70 19. A machine of the class described having a traveling paper carriage, a consecutive numbering mechanism, advancing means normally advancing said consecutive numbering mechanism after a number has been printed, printing means

- for said consecutive numbering mechanism urged in a direction to cause consecutive numbers to be printed, two restraining devices normally restraining said printing means, and means controlled by said carriage in a predetermined columnar position thereof for releasing both of said restraining devices and simultaneously disabling said advancing means, said carriage controlled means being operable in another predetermined columnar position of said carriage to release one of said restrained devices without disabling said advancing means, and manually controlled means for releasing said second restraining means in said second columnar position of said carriage.
- 10 20. A machine of the class described having a traveling paper carriage, a total taking means, a consecutive numbering mechanism, means urging said consecutive numbering mechanism toward printing position, advancing means normally operated to advance said consecutive numbering mechanism after a consecutive number has been printed, two latching devices for restraining said numbering mechanism against movement to printing position, means controlled by said paper carriage in a predetermined columnar position thereof for releasing both of said latching devices and simultaneously disabling said advancing means, said carriage controlled means being operable in another or second predetermined columnar position of said carriage to release one of said latching devices while the other latching device remains in latched position and while said advancing means remains in operative condition, and means conditioned by said total taking means for causing said second latching device to be re-
- 15 leased in said second predetermined columnar position of said carriage.
21. A machine of the class described having a traveling paper carriage, total taking means, a consecutive numbering mechanism, printing means for causing the consecutive number in said mechanism to be printed, an advancing means normally operating to advance said consecutive numbering mechanism as an incident to a printing operation, means under the control of said paper carriage for causing the same consecutive number to be printed in a predetermined number of columnar positions of said carriage, and means controlled by said total-taking means for causing said advancing means to automatically advance 10 said consecutive numbering mechanism in one of said predetermined columnar positions of said carriage after a repeated consecutive number has been printed.
22. A machine of the class described having a traveling paper carriage, total taking means, a consecutive numbering mechanism, printing means for causing the consecutive number in said mechanism to be printed, an advancing means for said consecutive numbering mechanism, means 25 controlled by said paper carriage causing the same consecutive number to be printed in a predetermined number of columnar positions of said carriage, and means under the joint control of said paper carriage and said total taking means 30 causing said consecutive numbering mechanism to be automatically advanced after the printing of said repeated consecutive number in a predetermined columnar position of said carriage.

ROBERT L. MULLER. 35
